UNITED STATES PATENT OFFICE.

LEOPOLD KOENIG, OF NEW YORK, N. Y.

DESIGN FOR TRIMMING.

SPECIFICATION forming part of Design No. 13,304, dated September 19, 1882.

Application filed August 16, 1882. Term of patent 3½ years.

To all whom it may concern:

Be it known that I, LEOPOLD KOENIG, a citizen of Austria, residing at New York, in the county and State of New York, have invented and produced a new and original Design for Trimming, of which the following is a specification, reference being had to the accompanying drawings, forming part thereof.

The design consists of a number of smooth-surfaced squares bordered by tufts of chenille, as hereinafter more fully set forth.

In the accompanying drawings, Figure 1 is a face view of my design. Fig. 2 is a transverse sectional view.

Similar letters indicate corresponding parts.

In the drawings, the letter *a* designates the smooth-surfaced squares. These smooth-surfaced squares are surrounded by tufts *b*, of

chenille or similar material. By this arrangement I produce a trimming of a varied surface, and one which produces a very pleasing effect on the eye.

What I claim as new, and desire to secure by Letters Patent, is—

The design for trimmings herein shown and described, the same consisting of smooth-surfaced squares bordered by tufts of chenille, forming a varied surface.

In testimony whereof I have hereunto set my hand and seal in the presence of two subscribing witnesses.

LEOPOLD KOENIG. [L. S.]
